UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

AUTOMOBILE-HORN.

1,216,828.

Specification of Letters Patent. Patented Feb. 20, 1917.

Application filed September 29, 1913. Serial No. 792,257.

To all whom it may concern:

Be it known that I, RAY H. MANSON, a citizen of the United States, residing at Elyria, in the county of Lorain and State 5 of Ohio, have invented certain new and useful Improvements in Automobile-Horns; and I do hereby declare the following to be a full, clear, and exact description of my invention, such as will enable others skilled in 10 the art to which it appertains to make and use the same.

My invention relates to signaling devices, generally known as automobile horns for use upon automobiles, motor cycles, motor 15 boats, etc., or, in fact, in any position where such a signaling device is desired.

My invention relates particularly to electric automobile horns, and in the embodiment illustrated, I have shown what is 20 known as a vibrator horn.

One of the objects of my invention is to increase the sound produced by horns of the vibrator type. One of the ways of accomplishing this is to increase the size or number 25 of the magnets and reduce the friction of the parts, so as to devote the entire or almost the entire energy of the magnet to produce noise.

Other objects of my invention and the 30 invention itself will perhaps be better understood from the description of the particular embodiments illustrated.

Figure 1 is a section through an embodiment of my invention, showing certain of 35 the parts in elevation.

Fig. 2 is a rear end view of the modification shown in Fig. 1.

Fig. 3 is a section through a second embodiment, showing certain of the parts in 40 elevation.

Referring now to the drawing and to the particular embodiments of my invention illustrated therein, and first to the embodiment illustrated in Figs. 1 and 2, at 4 is illustrated a frame piece which is here shown as having a flange 5 dished out as shown at 6 and a rear hollow portion 7. I have illustrated this form of frame piece for convenience, though any suitable form may be employed. A sonorous member, such as a diaphragm 8 extends over the opening 6 and is clamped to the outer edges of the flange 5 by some suitable means, such as screws 9 which extend through a casing front 10, extended over the face of the diaphragm. This

casing front is provided with an opening 11 and a flange 12 around the opening. A resonator 13 may be fitted in this flange and the opening 11 is provided for the egress of sound waves from the diaphragm. The diaphragm may be provided with an anvil 14 for a purpose to be described.

Suitable means are provided for furnishing motor power to operate the diaphragm, which is here shown as electromagnetic 65 means 15. In the form illustrated in Figs. 1 and 2 I have shown four electromagnets for performing these functions, all mounted within the frame, and adapted to exert influence upon the armature 16, which may 70 be mounted in any suitable position and which is here shown as mounted to the rear of the magnets and supported from the frame piece through a spring 18 which is connected at one end to the frame piece by 75 any suitable means, such as a screw 19, and which is connected to the center of the armature by any suitable means, such as a screw 20.

A switch is provided for controlling the 80 circuit of the electromagnetic means, here illustrated at 25 and consisting of a contact 26 supported from a spring 27 which is connected to the frame. The spring 27 is so stressed as to follow movements of the armature, normally resting at one end 29 against a stud 30 on the armature. The stud 30 is best made of insulating material. A second contact 31 of the switch 25 is supported from an adjustable screw 32, which may be carried by a bridge 33 connected to the frame piece in any suitable manner, such as by screws 34 and 35.

I am aware that previous efforts have been made to increase the efficiency of the horn 95 by employing more than two magnets, which is the custom in most horns. I am also aware that means have been provided for furnishing the diaphragm striker with slideable bearings, which furnish considerable frictional resistance to the operation, especially after the horn has been in use for some time, when dirt and dust collect in these bearings. The increased loudness resulting from the use of the four magnets or from increasing 100 the size and strength of the two magnets is much reduced, owing to this frictional resistance. On the other hand, with a strong magnetic field, a striker free at one end is apt to be vibrated sidewise when forcibly 110

attracted by a strong magnetic field, striking the diaphragm at an angle and consequently a weakened blow.

In my invention I have provided means 5 for properly directing the striker to the diaphragm and eliminating all frictional resistance. I also arrange the parts so that the resultant of the attractions upon the armature passes through the striker.

10 In the form shown in Figs. 1 and 2, each of the magnets 15 is placed so that it attracts one of the corners of the armature 16, so that the resultant of the attractions passes through the center of the armature, which is 15 attached to one end of the spring 18. The spring 18 is best made as long as possible, so that for the short arcs in which the armature moves it is moving for all practical purposes in a straight line. The striker 40 is 20 adapted to operate the diaphragm when the armature is vibrated. In the form shown in Fig. 1 this member is connected preferably to the center of the armature 16. The end adjacent the diaphragm instead of being 25 free or operated in bearings, as has been the case in previous horns of this character, is connected to a member 41, here illustrated as a spring supported in any suitable manner from the frame and here shown as connected thereto by screws 42. The other end of the member 41 is connected, as shown, at 30 43 to the striker 40. The member 41 is best made as long as possible, so that for the small arcs in which the end 43 of this member moves, such arcs may be considered a 35 straight line.

When the magnets are energized, each one acts upon a corner of the armature 16, pulling the armature straight down toward the 40 diaphragm and moving it so that it will be parallel to the diaphragm throughout its movement, the spring 18 being connected to the center, as shown. The end of the striker next the diaphragm cannot vibrate, being 45 directed in a straight line to the diaphragm by the member 41, which accomplishes this purpose without exerting any frictional resistance. The spring 41 may be made weak, so that no resistance at all will be exerted 50 against the efforts of the magnets, thus serving the directing function without offering any resistance whatsoever to the magnets.

In the modification shown in Fig. 3 I have 55 illustrated a horn showing the frame piece at 100, which is provided with a flange 101 around the edge. The diaphragm 102 is clamped between the flange 101 and the casting front 103, which is provided with an opening 104 for the egress of sound waves. 60 The edges of this opening are preferably turned up to form a flange shown at 105 to which a resonator 106 may be connected. The means for furnishing motor power to operate the diaphragm, here consisting of 65 electromagnets 107, may be connected to the

bottom 108 of the member 100. The bottom 108 is provided with an opening 109 through which a rod 110 extends, being associated with the armature 111 and here shown as connected thereto. The armature 111 may 70 be supported from the frame piece in any suitable manner, such as by a bracket 112 and a spring 113. The other end of the member 110 may be connected by a spring 75 112 to the frame through any suitable member such as a screw 113 and a support 114. A controlling switch is shown at 115. In this form the armature strikes the diaphragm after its release by the magnet, the member 110 serving to open the switch and 80 to direct the armature 111. The member 111 may be provided with a hammer 120 which strikes a diaphragm 121 when the armature is vibrated.

I have shown these embodiments of my 85 invention for the purpose of illustrating the invention and not that I wish to be limited to the form and details shown, as I contemplate numerous and extensive departures therefrom.

I claim:—

1. In an automobile horn, the combination 95 of a frame, a sound producing diaphragm supported from the frame, electromagnets for supplying energy to operate the diaphragm, an armature for said magnets, a spring connecting the armature to the frame, means to attach the armature to the spring applied at the center of the armature, an electric switch controlling the circuit of 100 the magnets governed by the armature, an anvil on the diaphragm, a stem connected at one end to the center of the armature for transmitting the motion of the armature to the diaphragm and vibrating the same, and 105 a spring supported from the frame connected at one end to the other end of the stem for directing the same.

2. In an automobile horn, the combination 110 of a sonorous diaphragm, a frame, a member 115 adapted to be reciprocated to strike the diaphragm to cause it to sound signals, an armature for reciprocating said member to which the member is connected at one end, a leaf spring connected at one end to the other 120 end of the reciprocating member, said leaf spring being connected at its other end to the frame and adapted to direct the reciprocating member when the same is reciprocated, a spring for connecting the armature 125 to the frame connected to the center of the armature, four electromagnets for operating the armature, one acting on each corner of the armature when said magnets are energized and a switch controlling the circuit of the magnets governed by the armature.

3. In an automobile horn, the combination 130 of a frame, a diaphragm chamber formed in said frame, a sonorous diaphragm in said frame and an electromagnet chamber in said

frame, an electromagnet in said chamber, an armature for said magnet, a stem connected to said armature through which the armature operates the diaphragm, a pair of leaf springs connected to the frame, one of said springs being in the magnet chamber and the other of said springs being in the diaphragm chamber, and a switch having contacts in the circuit of the magnet controlled by the armature.

4. In an automobile horn, the combination of a frame, a diaphragm chamber formed in said frame, a sonorous diaphragm in said frame, a magnet chamber formed in the frame, a magnet in said chamber, an armature controlled by said magnet for actuating the diaphragm, a leaf spring in the magnet chamber supported from the frame and connected to the armature, a second leaf spring in the diaphragm chamber, a rod connecting said second spring to the armature and a switch having contacts in the circuit of the magnet controlled by said magnet.

5. In an automobile horn, the combination of a frame, a pair of chambers formed in said frame, a sonorous diaphragm mounted in one of said chambers, a magnet in said frame, a switch for said magnet in the other

of said chambers controlled by said magnet, a pair of leaf springs supported from the frame, one of said leaf springs being in each of said chambers, an armature for causing the actuation of the diaphragm controlled by said magnet and connected to one of said springs and a stem connecting the other of said springs to said armature.

6. In an automobile horn, the combination of a frame, a pair of chambers formed in said frame, a sonorous diaphragm in one of said chambers, a magnet in said frame, a switch in said frame having contacts in the circuit of the magnet controlled by said magnet, an armature for said magnet for causing the actuation of the diaphragm, a pair of leaf springs, one in each of said chambers connected to the frame, an armature carried by one of said springs and a stem connecting the other of said springs to the armature.

In witness whereof, I have affixed my signature in the presence of two witnesses this 27th day of Sept., 1913.

RAY H. MANSON.
